CLAIM

The ornamental design for a control unit for whirlpool baths or the like, as shown and described.

DESCRIPTION

FIG. 1 is a perspective view of a control unit for whirlpool baths or the like embodying my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side being a mirror image.

The broken line showing of the time in FIGS. 1 and 2 is for illustrative purposes.
